CLAIM

The ornamental design for a cappuccino making adapter for an espresso machine, as shown and described.

DESCRIPTION

FIG. 1 is a front perspective view of a cappuccino making adapter for an espresso machine showing my new design;

FIG. 2 is a right-hand side elevational view thereof;

FIG. 3 is a top plan view thereof;

FIG. 4 is a bottom plan view thereof;

FIG. 5 is a front elevational view thereof;

FIG. 6 is a left-hand side elevational view thereof;

FIG. 7 is a rear elevational view thereof; and

FIG. 8 is a reduced scale front perspective view thereof.

The broken line showing of a fragmentary portion of an espresso machine is illustrative of environmental structure only and forms no part of the claimed design.
